Norman Clayton Jenkins, 214 Thomas Ave.,
Nutter Fort, W. Va. 26301

Filed Nov. 1, 1965, Ser. No. 87,971

Term of patent 14 years

(Cl. D33—14)

The dominant features of my design reside in those portions shown in full lines on the drawing.

I claim:

The ornamental design for a table or the like, substantially as shown and described.
